RANGE INDICATOR

Nils T. Almquist, New Britain, Conn., assignor to
 Landers, Frary & Clark, New Britain, Conn., a
 corporation of Connecticut

Application February 17, 1941, Serial No. 379,192

1 Claim. (Cl. 116—133)

The present invention relates to indicators for electric ranges and more particularly to a novel visual indicator including a lamp, a refracting member or bull's-eye, and an adjustable screen for varying the intensity of light passing from the lamp through the bull's-eye. A visual indicator made in accordance with the present invention is adapted for use in combination with an electric switch having manually adjustable means for regulating the amount of current supplied to an electric heating element or other appliance in order to control the heat output therefrom. Accordingly it is an object of the present invention to provide a novel indicator wherein the adjustable screen is operably connected to the manual switch adjustment means so that as the current supply rate is varied by manual adjustment of the switch the intensity of light passing through the bull's-eye is likewise varied.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claim.

In the accompanying drawing:

Figure 1 illustrates a plan view of a series of control knobs for controlling the heat output of individual electric heating elements and a series of bull's-eyes for indicating the degree of heat output from each element;

Fig. 2 is an enlarged cross-sectional view taken along line 2—2 of Fig. 1;

Fig. 3 is an enlarged cross-sectional view taken along line 3—3 of Fig. 1; and

Fig. 4 is a plan view of a manually operable knob designed for use with an indicator made in accordance with the present invention.

Referring to Figure 1 of the drawing, there is illustrated a control panel 10 of an electric range indicated generally by the letter R. Rotatably mounted outwardly of the panel are a series of manually operable knobs 12, each of which controls the setting of an individual electric switch illustrated generally at 14, one such switch being provided for each heating unit or element (not shown) of the range. In the present instance there are four such units as indicated by the four knobs on the panel 10. However, since the operation of each indicator is the same, a description of one will be sufficient to explain the invention.

In the present instance each switch 14 is

adapted to regulate the current supplied to the controlled heating element and to determine the intensity of heat output over the entire heat range from the "off" to the full "on" position and to provide intermediate adjustments therebetween. The exact structure of the switch is not material to the invention and may be any one of a number of standard switches designed to provide the type of regulation indicated. The knob 12 illustrated in Fig. 4 is marked to indicate the "off," "simmer," "very low," "low," "medium," and "high" settings of the switch and is further graduated to indicate intermediate adjustments.

In order to more clearly illustrate one embodiment of the present invention, one of the switches 14 controlled by the knob 12 is shown operably mounted on the range R. More specifically, the range includes a panel 16 having an opening 18 over which is positioned a vertical mounting plate 20 parallel with and forwardly disposed from the plane of the range panel 16 and having a peripheral lip 22 secured to the panel A in any suitable way. A vertical outer wall 26 overlies the mounting plate 20 and is provided with a peripheral lip 28 which engages the range panel 16. The indicator panel 10 is located outwardly of the wall 26 and is held in position when the device is assembled by the switch knobs 12.

The switch 14 is mounted by means of a threaded collar 32 which extends through aligned openings in the mounting plate 20 and the outer wall 26 and secured thereto by means of the nut 34. Extending outwardly through the threaded collar is a rotatable switch shaft 36 which carries the switch adjustment knob 12 on its outer end. Located in an opening 40 in the panel 10 and secured to the shaft adjacent the collar 32 is a sleeve 38 which carries a cam plate 42.

As is shown in Figure 1, the cam 42 is a spirally developed plate member having a radius gradually diminishing from a maximum at point M to a minimum at point N.

In accordance with the present invention the cam 42 is adapted to regulate the amount of light passing from a light bulb B disposed rearwardly thereof through a bull's-eye 44 disposed forwardly thereof. The bulb B is mounted in a socket 46 which is secured as by a bolt and nut 48 to a shelf 50 extending from the casing of the switch 14 and is electrically connected so as to supply the bulb with current when the knob 12 is moved from the "off" position. In order to remove the bulb and to permit the passage of

light to the bull's-eye, a suitable hole 52 is cut in the mounting plate 20. Forwardly thereof the outer wall 26 is provided with a smaller hole 54 so disposed as to be entirely covered by the cam when the periphery of maximum radius M is in line therewith and entirely uncovered when the periphery of minimum radius N is in alignment. Similarly, the intermediate portions of the cam will cover predetermined areas of the hole and will vary the amount or intensity of light passing outwardly through the hole 54 and the bull's-eye 44 from the bulb B. Forwardly of the cam and directly in front of the hole 54 is the bull's-eye which may be of any desirable shape; that shown being triangular. The bull's-eye comprises a piece of colored glass which for better refraction of light may be provided on its rear surface with a series of equally spaced horizontal serrations or prismatic ribs 58. The variation in thickness of the bull's-eye resulting from the formation of the ribs 58 in the glass causes the bull's-eye to refract the light into parallel lines of brightness spaced by parallel lines of darkness. The number of lines thus produced by the light from the bulb will be dependent upon the position of the cam and the number of ribs 58 receiving rays of light directly from the uncovered portion of the hole 54. Thus, when the knob 12 is in the "off" position and the periphery of the cam of maximum radius overlies the opening 54, no light will reach the bull's-eye. However, as the knob is rotated the cam rotates therewith, and, beginning at the top of the bull's-eye, one after another lines of brightness appear until the knob reaches the full "on" or "high" position. In the latter position the entire bull's-eye is illuminated with alternately spaced lines of brightness and darkness.

In order that the light from one bulb will not shine through the opening provided for the bull's-eye of an adjacent switch, the rear surfaces of the panels and walls are blackened to prevent the light straying by reflection. It will likewise

be noted that the bull's-eye serves a second purpose, inasmuch as it acts as a reference point for the markings on the dial surface.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween.

I claim as my invention:

In an electric current control device for an electric heating element, a panel, a shaft extending therethrough and rotatably adjustable to any predesired selected position between minimum and maximum, a knob secured to the forward end of said shaft adjacent said panel and having on its exposed face indicia for indicating the setting of said shaft, said panel having an opening disposed beyond and adjacent to the periphery of said knob, a bull's-eye in said opening for refracting the light passing therethrough and directing it onto the adjacent portion of the exposed face of said knob, a source of light behind said panel rearwardly of said opening, and a spirally developed opaque cam plate secured to said shaft so as to rotate therewith and located behind said panel between said source of light and said bull's-eye, said cam plate being so graduated that when said knob and shaft are in their minimum positions, said plate completely screens said bull's-eye from the source of light and, as the knob moves towards maximum position, said cam plate gradually exposes said bull's-eye to said source of light.
